SAUTE FORK

Harvey F. Trainum, 3024 McLemore St.,
Norfolk, Va. 23509

Filed July 3, 1969, Ser. No. 18,043

Term of patent 14 years

Int. Cl. D7—03

U.S. Cl. D44—29

FIG. 1 is a top plan view of a saute fork showing my new design;

FIG. 2 is a left side elevational view;

FIG. 3 is a bottom plan view;

FIG. 4 is an enlarged scale sectional view on line 4—4 of FIG. 1;

FIG. 5 is an enlarged scale sectional view on line 5—5 of FIG. 3; and

FIG. 6 is an enlarged scale fragmentary elevational view on line 6—6 of FIG. 5.

I claim:

The ornamental design for a saute fork, as shown.
